UNITED STATES PATENT OFFICE.

THOMAS W. VANCE, OF COLUMBUS, OHIO.

OVERALLS.

1,071,483.

Specification of Letters Patent. Patented Aug. 26, 1913.

Application filed October 9, 1911. Serial No. 653,543.

To all whom it may concern:

Be it known that I, THOMAS W. VANCE, a citizen of the United States, residing at Columbus, in the county of Franklin, State of Ohio, have invented certain new and useful Improvements in Overalls; and do hereby declare the following to be a full, clear, and exact description of the invention, such as will enable others skilled in the art to which it appertains to make and use the same.

This invention relates to overalls and more especially to a combination garment including a waist or jumper and trousers of the open seam type and which I term "auto-
alls."

The primary object of my invention is to provide a garment of the above character in which the trousers will be formed with open
seams so that they may be fastened on the inside or outside of the leg and thus permit the adjustment thereof quickly and easily over any style of trousers and yet leave them smooth and form a protection in use.

25 A further object of the invention is to combine the trousers with a novel form of jumper with an apron, the garment being especially adapted for use by motorists and providing a cover for the clothes in case it becomes necessary to make any repairs.

With the above and other objects in view the invention consists of certain other combinations and arrangements of parts, as will be hereinafter more fully described and claimed, it being a still further object of the invention to provide a device which will not be likely to get out of working order.

In the drawings: Figure 1 is a front elevation of a combination garment constructed in accordance with my invention, the trousers having open seams positioned at the outer sides of the legs. Fig. 2 is a rear elevation thereof. Fig. 3 is a view similar to Fig. 1 but shown with a pair of trousers having open seams located upon the insides of the legs and with a different arrangement of pockets, the overhanging apron being folded upwardly. Fig. 4 is a rear elevation of the trousers shown in the garment in Fig. 50 3 of the drawings.

Referring to the drawings in detail, there is shown my improved combination garment and in referring to Figs. 1 and 2 there is shown a jumper 10 comprising a front section 11, a back section 12 and sleeves 13 all of which are formed from a single sec-

tion of material and provided with a reinforced binding 14 around the exposed edges thereof. A neck opening 15 is formed in the section between the arms and the portion thereof at the front section of the jumper is left open as shown at 16 for the entrance of the head therethrough, after which the reinforced portion of the neck band may be secured together by buttons or other suitable fastening means 17 and a pocket 18 is also provided upon the front section of the jumper as shown.

From an inspection of the drawings, it will be seen that the sleeves 13 are formed by lateral extensions of the material forming the front and back sections of the jumper and that the same are formed with a seam 19 at their lower edges and that the back section is reduced in size relative to the front section, so that the front section will fully cover the front portion of the body and shoulders and so that sufficient room or space will be left between the side portions of the sections to permit free movement of the arms and yet without exposing any parts of the clothing which would be likely to be soiled. Straps 20 are connected to the sides of the back section 12 adjacent the lower end thereof and are adapted to be extended around the front section and downwardly in an inclined position and secured by buttons or other fasteners 21 and terminate above the apron portion 22 of the jumper which is secured to the trousers of the garment as shown at 23 whereby the apron will overhang the trousers and form an additional protection where the same is most subject to wear.

The trousers shown in Figs. 1 and 2 of the drawings are formed of front sections 24 and back sections 25 which are suitably joined at the back and front along the inside and crotch while the outer edges thereof are left open and provided with a surrounding reinforced binding 26 as shown. A waist band 27 is provided for the trousers and comprises a front portion 28 and a back portion 29, the back portion being provided with extended ends 30 secured by fastening means or buttons 31 while each rear section is provided with extended tongues 33 which are formed therewith or attached thereto and are of the required length to permit the back sections to overlap the front sections at the outer edges thereof so that the tongues may be secured by similar fastening means.

31 used in connection with the extended ends of the waist band. It will also be noted that the lower tongue is longer than the upper tongue and is made adjustable as shall be found desirable and pockets 34 are secured to the front sections at the knees of the trousers and serve to receive the waste with which the machine is cleaned and also serve as knee pads while the other pocket or 10 pockets as shall be found desirable may serve for carrying tools and the like. A pair of straps or depending tongues 35 are provided at the lower edge of the back section of the jumper and are provided with 15 fastening means 36 to be secured to the back portion of the waist band 27 upon opposite sides of the central joining line of the front and back sections of the trousers, the front section of the jumper being connected to the 20 front portion of the waist band and overhanging the front sections of the trousers for the purpose hereinbefore set forth.

In the structure shown in Figs. 3 and 4 of the drawings, the jumper is of the same 25 design while the trousers are formed of front sections 37 and back sections 38, the front and back sections of each leg of the trousers being connected at the outer sides and formed at their inner edges with open 30 seams and with reinforced bindings 39 while the inner edges of the back sections are formed with extensions 40 which are secured in overlapped relation relative to the front sections at their inner edges by fastening 35 means 41, the adjacent inner edges of the front sections being also secured together while the inner edges of the back sections are left open as shown at 42 and are provided at the waist band 43 with securing means 44. 40 Knee pockets 45 are also provided for the front sections and upper side pockets 46 are secured to the outer edges of the front and rear sections for any desired purpose.

From the foregoing description in connection with the accompanying drawings, it will 45

be seen that a very simple and efficient form of combination garment of the character named is provided which may be especially desirable for the purposes stated and wherein the same may be readily secured on the body 50 and will serve to properly protect the clothing without in any manner bunching the same, it being understood that the garments are to be made in such sizes that the adjustability of the leg sections will accomplish the 55 functions set forth.

I claim:—

1. In a combination garment, a pair of trousers and a jumper secured to the trousers, said jumper comprising a front section, 60 back section and arms formed of a single piece of material and secured to the front portion of the waist band of the trousers so as to overhang the same to form an apron.

2. A body garment comprising a front 65 section, a back section and sleeves formed of a single piece of material, the sleeves comprising lateral extensions having their longitudinal edges in a neck opening formed in said sections between the arms and provided 70 with a detachable closure and straps carried by the sides and lower edge of the back section to be secured around the front section and to the waist band of a pair of trousers respectively.

3. A combination garment comprising a jumper having an extended front section, trousers having adjustable open seams connecting front and back sections of the trousers, said extended portion of the front section of the jumper being connected to the front portion of the trousers and overhanging the same. 75

In testimony whereof, I affix my signature, in presence of two witnesses.

THOMAS W. VANCE.
